(57) **CLAIM**

The ornamental design for an interface module for an intraoral sensor, as shown and described.

DESCRIPTION

FIG. 1 is a perspective view of an interface module for an intraoral sensor showing my new design;
FIG. 2 is a front elevational view thereof;
FIG. 3 is a rear elevational view thereof;
FIG. 4 is a right side view thereof;
FIG. 5 is a left side view thereof;
FIG. 6 is a top plan view thereof; and,
FIG. 7 is a bottom plan view thereof.

The broken lines shown in the figures are included for the purpose of illustrating portions of the interface module for an intraoral sensor and form no part of the claimed design.
